UNIVERSAL DIE IMPLEMENT

John A. Hagerstrom, Cranford, and John F.
Hagerstrom, Elizabeth, N. J.

Application April 11, 1940, Serial No. 329,062

8 Claims. (Cl. 164—94)

This invention relates to an implement for therewith die punching holes of a large variety and sizes through materials. Its principal objects are to affect readiness and convenience in this type of work, increased speed of production, enhanced accuracy, and improved products, as well as improved means for disassembling the universal complementary die plate and punch-guiding plate of the implement, for reconditioning them.

Other objects and advantages will hereinafter appear.

In the accompanying drawings,

Fig. 1 is a plan view of the implement constituting the invention.

Fig. 2 is a front elevation of the implement shown in Fig. 1.

Fig. 3 is a side elevation of the implement shown in Fig. 1.

Fig. 4 is a transverse cross-sectional elevation, taken on the line 4—4 of Fig. 1, showing details of the implement.

Fig. 5 is a fragmentary plan view, showing a detail of the invention.

Fig. 6 is an elevational view showing a detail of the invention.

The implement has a base 1 with a pair of recesses 2 for bolting it to any bench, table, or punch press, and on said base is formed a post 3 having a bore 4. A rest 5 is formed on said base opposite to the post 3 having a punch clearance hole 6 with a receiving pocket 7 thereunder for the punched out parts, the top of rest 5 being level with that of the post 3, and a web 8 joining said rest and post together with the base 1 for strengthening the structure. On the post 3 is seated the end of an arm 9 of a semi-circular die-plate 10, and above said plate is located a punch-guiding plate 11 having a similar arm 12. In opposing depressions 13 formed in the arms 9, 12 is lodged a fitting 14 comprising a pair of arms 15, Figs. 1, 3, 6, within said depressions, forming part of a hub 16 having a bore 17 that registers with bores 18 of the arms 9, 12, and between the arms 15 is formed a gap 19 which thereby creates the separating working gap 20 between the die plate 10 and guide plate 11. A shaft 21 journaled in bore 4 is provided with a narrower shank 22 that passes through bores 17, 18, and a nut 23 threads over said shank against the arm 12, by which means the plates 10, 11 are jointly pivoted to swing together about the axis 24 of shaft 21, as viewed in Fig. 1. Screws 25 additionally secure the plates 10, 11 to the terminals of arms 15 of the fitting 14. By 55

unthreading the nut 23 and screws 25, the plates 10, 11 may be readily removed and individually separated from the fitting 14, for conveniently grinding, reconditioning, and repairing of these plates.

In the punch guiding plate 11, along an arc 26 concentric with the axis 24, is formed a series of guide holes 27, ranging in size from a largest median one 27a and diminishing gradually to smallest openings 27b, as illustrated, and each hole having a stamped indication of its size, as $\frac{1}{8}$, $\frac{5}{32}$, etc. The plate 10 is provided with concentric complementary die holes 28 for the holes 27, and in the underside of the plate 11 is formed a series of recessed holes 29 along an arc 30 which is concentric with the arc 26 and axis 24, providing a hole 29 for each complementary pair of holes 27, 28 which is radial thereto as well as with the axis 24, as shown in Fig. 1. Each hole 27 is provided with a notched outlet 31 to the edge 11a of the die plate 11, the side 32 of said outlet being radial to the hole as well as to the axis 24, and thereby serving to conveniently align a marked centre-line upon work to be punched with the axis of any selected registering holes 27, 28. The combined plates 10, 11 may be therefore swung about the axis 24 of hinge shaft 3 to bring any one of the complementary holes 27, 28 into registry with the clearance hole 6 in rest 5, which punch clearance hole is thus common to all of said die holes.

In the rest 5 is formed a vertical bore 33, the axis of which is in the arc 30 of holes 29 and is radial to both the punch clearance hole 6 and the axis 24, and slidably within the bore 33 is a plunger 34 pressed upwardly by a spring 35 thereunder and having a pin 36 which is fittingly enterable into any one of the recessed holes 29, belonging to a complementary pair of holes 27, 28 that may be set in registry with the clearance hole 6. In a hub 37 forming part of the rest 5 is formed a horizontal bore 38 perpendicularly to the bore 33 having therein a rock shaft 39 terminating in an eccentric pin 40 that fits in an horizontal slot 41 formed in the plunger 34. A crank pin 42 secured to the shaft 39 protrudes through an arcuate slot 43 in hub 37. When the plunger 34 normally interlocks its pin 36 with any one of the holes 29 by the tension of the spring 35 its slot 41 maintains the eccentric pin 40 in the position shown and thereby disposes the crank 42 vertically, Fig. 3. But when said crank is swung downwardly in the direction of the arrow, it rocks the shaft 39 and pin 40, and the latter actuates the plunger 34

downwardly and removes the pin 36 from the hole 29, thereby unlocking the die plate 10 for relocking any selected complementary die holes 27, 28 into registry with the clearance hole 6 of rest 5.

From the post 3 projects a wing 44 having a depressed seat 45 on which is slidable in the plane of the gay 20 of plates 10, 11 a leg 46 of a squaring tool 47, the latter having a comple- 10 plane of the gap 20 of plates 10, 11 a leg 46 of 15 slidable parallelly to a line 51 passing through axis 24 and centre of clearance hole 6, whereby the leg 48 is settable at or toward and away from said centre, the scale 49 is readable with relation to a mark 51a on wing 44 having a precise distance from said centre, and a thumb-screw 52 threads into wing 44 against a clamp 53, bearing upon the leg 46, which secures the square in any set position. A slide 54 movable along leg 48 carries a clamp 55 embracing said leg and securable on the latter with a thumb-screw 56, whereby the working terminal edge 54a of said slide may be adjusted to any position toward and away from centre line 51. The leg 48 is provided with an angular notch 57, whereby 20 when the square 47 is reversely mounted in the implement, as shown in Fig. 5, said notch is situated astride the centre line 51.

When it is desired to utilize this implement for production work, its plates 10, 11 may be swung about axis 24 to bring into registry with the fixed clearance hole 6 any one of selected complementary holes 27, 28, as may be required for a job, the crank 42 is manipulated for unlocking said plates and relocking them to the rest 5, and then the square 47 and gauge 54 are set in accordance with the situation of the hole to be punched in the sheet metal, plate, or other article constituting the job, and the latter is inserted in gap 20 in guidance of said square and gauge. A corresponding punch 58 is then inserted into the selected hole 27, and the punch is struck with any hammer, foot press, or power press, as the work may require, the base 1 of the implement having been previously properly secured as may be required by the hammer or press. The implement may be readily and conveniently reset and relocked for any other selected holes 27, 28, its tools 47, 54 readjusted for the required job, and other punching operations may be then performed. On resetting the tool 47 to the position shown in Fig. 5, any disk or symmetrially formed piece 58a may be placed in its notch 57 and guided thereby for punching a hole 59 in precise location in such piece as the job may require.

Variations may be resorted to within the scope of the invention, and portions of the improvements may be used without others.

Having thus described our invention, we claim:

1. A universal die implement having the combination of a die plate, a punch guiding plate thereover, a fitting between said plates comprising a hub having a pair of projecting arms one under the other with a gap between them, each of said plates having a recess for receiving one of said arms to provide a gap between said plates for the material to be punched, said plates together with said fitting being swingably mounted about a common axle, said plates having a series of various sized complementarily registered die and guide holes in an arc concentric with said axle, means for each of said complementary holes to register them with a predetermined working location centre and to lock said plates in said location centre, and a

location centre, and said plates and fitting being each disassemblable from each other and from said axle to permit reconditioning of said plates.

5. A universal die implement having the combination of a die plate, a punch-guiding plate thereover, said plates being fixed relatively to each other and providing a gap between them for material to be punched, said plates being swingably mounted about a common axis, said plates having a series of various sized complementarily registered die and guide holes in an arc concentric with said axis, means for each of said complementary holes to register them with a predetermined working location centre and to lock said plates in said location centre, a guiding plate with an alignment edge for material located within said gap being slidably mounted toward and away from a tangent of said arc, and means to secure said material guiding plate at any selected position.

3. A universal die implement having the combination of a die plate, a punch-guiding plate thereover, said plates being fixed relatively to each other and providing a gap between them for material to be punched, said plates being swingably mounted about a common axis, said plates having a series of various sized complementarily registered die and guide holes in an arc concentric with said axis, means for each of said complementary holes to register them with a predetermined working location centre and to lock said plates in said location centre, a guiding plate with an alignment edge for material located within said gap being slidably mounted toward and away from a tangent of said arc, means to secure said material guiding plate at any selected position, and said guiding plate having a scale for its setting adjustments.

4. A universal die implement having the combination of a die plate, a punch-guiding plate thereover, said plates being fixed relatively to each other and providing a gap between them for material to be punched, said plates being swingably mounted about a common axis, said plates having a series of various sized complementarily registered die and guide holes in an arc concentric with said axis, means for each of said complementary holes to register them with a predetermined working location centre and to lock said plates in said location centre, a material guide in said gap slidably mounted toward and away from a tangent of said arc, means to secure said material guide at any selected position, said guide having a gauge perpendicular thereto and movable therealong, and means to secure said gauge at any selected position.

5. A universal die implement having the combination of a die plate, a punch-guiding plate thereover, said plates being fixed relatively to each other and providing a gap between them for material to be punched, said plates being swingably mounted about a common axis, said plates having a series of various sized complementarily registered die and guide holes in an arc concentric with said axis, means for each of said complementary holes to register them with a predetermined working location centre and to lock said plates in said location centre, a material guide in said gap slidably mounted toward and away from a tangent of said arc, means to secure said material guide at any selected position, said guide having a gauge perpendicular thereto and movable therealong, means to se-

cure said gauge at any selected position, and said gauge having a scale for its setting adjustments.

6. A universal die implement having the combination of a die plate, a punch-guiding plate thereover, said plates being fixed relatively to each other and providing a gap between them for material to be punched, said plates being swingably mounted about a common axis, said plates having a series of various sized complementarily registered die and guide holes in an arc concentric with said axis, means for each of said complementary holes to register them with a predetermined working location centre and to lock said plates in said location centre, a material guide in said gap slidably mounted toward and away from a tangent of said arc, means to secure said material guide at any selected position, and said guide having means for embracing formed material.

7. A universal die implement having the combination of a die plate, a punch-guiding plate thereover, said plates being fixed relatively to each other and providing a gap between them for material to be punched, said plates being swingably mounted about a common axis, said plates having a series of various sized complementarily registered die and guide holes in an arc concentric with said axis, means for each of said complementary holes to register them with a predetermined working location centre and to

lock said plates in said location centre, a material guide in said gap slidably mounted toward and away from a tangent of said arc, means to secure said material guide at any selected position, said guide having a gauge perpendicular thereto and movable therealong, means to secure said gauge at any selected position, and said guide having means for embracing formed material.

8. A universal die implement having the combination of a die plate, a punch-guiding plate thereover, said plates being fixed relatively to each other and providing a gap between them for material to be punched, said plates being swingably mounted about a common axis, said plates having a series of various sized complementarily registered die and guide holes in an arc concentric with said axis, means for each of said complementary holes to register them with a predetermined working location centre and to lock said plates in said location centre, each of the guide holes in said punch-guiding plate having an outlet to and through the rim of said plate, and each of said outlets having an edge radially with said axis, for aligning a mark upon any work to be punched with said radially disposed edge.
